UNITED STATES PATENT OFFICE.

GEORGE HENRY GARNET, OF ALLENTOWN, PENNSYLVANIA.

CAN-OPENER.

No. 919,151.

Specification of Letters Patent.

Patented April 20, 1909.

Application filed May 20, 1908. Serial No. 433,943.

To all whom it may concern:

Be it known that I, GEORGE H. GARNET, a citizen of the United States, residing at Allentown, in the county of Lehigh and State 5 of Pennsylvania, have invented certain new and useful Improvements in Can-Openers: and I do hereby declare the following to be a full, clear, and exact description of the invention, such as will enable others skilled in 10 the art to which it appertains to make and use the same.

This invention relates to devices for opening cans and other similar vessels; and it 15 consists in the novel construction and combination of the parts hereinafter fully described and claimed.

In the drawings, Figure 1 is a perspective side view of the can-opener. Fig. 2 is a plan view of the same when opening a sealed can. 20 Fig. 3 is a perspective view showing the device when opening a friction-top can.

A is the handle of the can-opener formed of a strip of metal bent double to form an open loop, and provided with parallel lugs b 25 at one end.

B is a blade secured between the lugs b by rivets c. The blade B is formed of suitably hardened steel, and it has a slot d at its front part.

30 D is a sharp cutting-edge on one side of the slot d. The end portion e is curved laterally out of line with the sharp point D' of the cutting-edge D, and it is provided with a notch f. The slot d is arranged substantially parallel with the handle A, and the notch f is arranged on the other side of the slot d from the point D' of the cutting-edge. The cutting-edge D is thrust through the metal of the can, and the notch f is pressed 35 into engagement with the bead or projection on the edge of the can, so that the said bead forms a fulcrum for the said cutting-edge which cuts when pressed upward and slid, around the can.

G is a beveled curved portion which projects at the middle portion of the blade B, and g is a similar curved projecting portion on the part e. The upwardly curved portions G and g are arranged at an obtuse angle with each other and they are thrust under the flange of a friction-top can, for the purpose of removing its said friction-top, as 45 shown in Fig. 3.

H is a downwardly curved portion at the middle part of the blade B which strengthens the cutting-edge and affords a fulcrum for a hook h at the lower and rear part of the blade. This hook is used for removing all kinds of caps, covers and closures to 50 which it can be applied, the point of the hook being slipped under one flange of the cap and the fulcrum H caused to bear on the top of the cap. The cap is then removed by an upward jerk of the handle A.

What I claim is:

1. A can-opener provided with a blade having a slot, said blade having a cutting-edge on one side of the said slot, and having on the other side of the said slot an outwardly curved portion provided with a beveled portion on one side and having a second outwardly curved portion arranged in front of the first said curved portion and arranged at an angle to it and the said cutting-edge. 65

2. A can opener provided at one end with a blade having an outwardly curved portion provided with a beveled portion on one side and having a second outwardly curved portion arranged in front of the first said portion and at an angle to it. 75

In testimony whereof I have affixed my signature in the presence of two witnesses.

GEORGE HENRY GARNET.
